UNITED STATES PATENT OFFICE

126,113

DESIGN FOR A VEHICLE LIGHTING UNIT

Eric B. Hallman, Philadelphia, Pa., assignor to
Electric Service Supplies Company, Philadelphia, Pa., a corporation of Pennsylvania

Application January 11, 1941, Serial No. 97,975

Term of patent 14 years

To all whom it may concern:

Be it known that I, Eric B. Hallman, a citizen of the United States and a resident of Philadelphia, county of Philadelphia, State of Pennsylvania, have invented a new, original, and ornamental Design for a Vehicle Lighting Unit, of which the following is a specification, reference being had to the accompanying drawing forming a part thereof, wherein:

Figure 1 is a perspective view of the vehicle lighting unit showing my new design; Figure 2 is

a bottom plan view thereof; Figure 3 is a side elevational view thereof; and Figure 4 is an end elevational view thereof.

In said drawing, the stippled areas represent translucent material which surrounds the centrally disposed light transmitting part formed of clear or transparent material.

I claim:

The ornamental design for a vehicle lighting unit, substantially as shown and described.

ERIC B. HALLMAN.
